TILLER FOR JET BOAT

John L. Buchler, Indianapolis, Ind., assignor to The
Buchler Corporation, a corporation of Indiana
Filed Aug. 8, 1960, Ser. No. 48,291
2 Claims. (Cl. 115—12)

The present invention relates to jet propelled watercraft and more particularly to means for steering and controlling the direction and speed of such craft.

At least one form of water jet-propelled boat involves an engine arranged to drive a turbine which is located within a conduit through the boat. Water is drawn into the conduit through an intake opening at the bottom of the boat, is pumped through the conduit by the turbine and is exhausted in a stream from the rear of the boat, the stream leaving the boat above the water within which the boat is floating or is supported. The propulsion principle depends directly on a basic law of physics which provides that every action has an equal and opposite reaction. Thus, as water is ejected astern, the boat moves forward.

A most effective way of steering and otherwise controlling the direction of movement of such jet-propelled watercraft is the deflecting of the jet of water as it leaves the rear of the craft. Thus, the jet may be deflected through various angles in a horizontal plane to turn or steer the boat and may be reversed and directed beneath the boat to cause rearward movement of the boat. Such jet boats are also usually provided with variable speed engines arranged to drive turbines which pump water to form the jet. Thus, a further means of controlling the jet boat and more particularly the speed thereof involves means such as a throttle control for changing the speed of the variable speed engine.

In the smaller type of boat such as is used by one or two fishermen and of a size comparable to a rowboat, it is desirable that these control means be easily operated and require little attention so as to leave the fisherman-operator as free as possible to fish. Therefore, it is a primary object of the present invention to provide improved jet boat control means, said means being easily operated and requiring little attention.

A further object of the present invention is to provide jet boat control means capable of operation by one hand to allow free use of the other hand for fishing.

Related objects and advantages will become apparent as the description proceeds.

The full nature of the invention will be understood from the accompanying drawings and the following description and claims.

FIG. 1 is a side elevation of a jet boat incorporating the control means of the present invention.

FIG. 2 is an enlarged vertical section of the rearward portion of the boat taken along the longitudinal axis thereof and showing in detail certain portions of the control of the present invention.

FIG. 3 is a top plan view of a portion of the structure illustrated in FIG. 2.

FIG. 4 is a horizontal section taken along the line 4—4 of FIG. 2 in the direction of the arrows.

FIG. 5 is a top plan view of the most rearward portion of the structure illustrated in FIG. 2.

For the purposes of promoting an understanding of the principles of the invention, reference will now be made to the embodiment illustrated in the drawing and specific language will be used to describe the same. It will nevertheless be understood that no limitation of the scope of the invention is thereby intended, such alterations and further modifications in the illustrated device, and such further applications of the principles of the invention as

2

illustrated therein being contemplated as would normally occur to one skilled in the art to which the invention relates.

Referring now more particularly to the drawings, there is illustrated a jet boat 10 having a hull 11, the hull being provided with an intake opening 12 communicating between the bottom of the boat and a turbine 13. The turbine 13 has a passage therethrough communicating between the intake opening 12 and a passage 15 through a tailpipe 16 secured to the rear of the boat. The turbine 13 is driven by a conventional marine engine 14 through a shaft 14A and functions to pump water from the intake 12 to and out of the rear of the boat. The water is formed into a jet by the converging surface 17 of an annular member 18 fixed within the passage 15, the jet leaving the boat at a point above the water line.

Fixed to the tailpipe 16 is a housing 20, one function of which is to contain a depending gate or slide 21 which is movable within a vertically extending opening 22 to various positions. There is provided means (described in detail below) for raising and lowering a shaft 23 which is reciprocally received within a suitable bore in the upper end of the housing 20. The gate or slide 21 is swivel mounted to the shaft 23 by a ball and socket connection 25. Thus, the gate 21, when in the position illustrated in FIG. 2, hangs freely within the housing 20. It should be noted that the upward end of the housing is sealed or completely closed off except for the bore receiving the shaft 23 and that there are no openings to allow the passage of water from the upward portion of the housing 20.

The housing 20 is provided with a cylindrical bore 26 of the same size or slightly larger than the exit end of the opening through annular member 18, said cylindrical bore 26 registering with the opening through the annular member 18. When the gate 21 is positioned as in FIG. 2 above the opening 26, the turbine 13 may pump a stream of water through the annular member 18, through the vertically extending opening 22 and the cylindrical opening 26 in the housing to be exhausted from the rear of the boat. The housing 20 also functions to provide a pivotal mounting for a pair of deflector plates 27 which are used for deflecting the stream of water to steer the boat.

The plates 27 are each pivotal about a vertical axis provided by suitable shafts extending through projections 28 extending from the housing 20, the plates 27 being positioned on opposite sides of the stream of water. In order to turn the boat in one direction, one of the plates 27 is pivoted into the jet stream by means of a steering quadrant 29 pivotally mounted on the housing 20 by means of a shaft 29A positioned directly between the pivotal mountings of the deflector plates, the quadrant 29 having a pair of depending elements 29B located outside of the deflector plates and arranged to pivot one or the other of the plates inwardly when the quadrant 29 is pivoted. The quadrant may be pivoted through the shaft 29A by means of steering mechanism described below.

A tiller, indicated generally by the numeral 35, is pivoted about a horizontal axis upon a tiller support 36 which has a depending cylindrical portion 37 received within a cylindrical bearing 40 fixed to the rear or transom 41 of the jet boat. A cylindrical element 42 is reciprocably received and pivotal within a vertically extending aperture within the cylindrical portion 37 of the tiller support. The tiller support is provided with an upwardly projecting yoke 44, each arm of which has pivoted thereon a link 43. Each of the links 43 has at its opposite ends a pair of slots 45 and 46 which extend longitudinally of the link and receive pins 47 and 48 fixed to the cylindrical element 42 and the tiller 35, re-

spectively. It can be appreciated that when the tiller 35 is raised from the solid line position of FIG. 2 to the dotted line position, the cylindrical element 42 will be moved downwardly and when the tiller is moved oppositely, the cylindrical element will be moved upwardly. The lowermost position of the tiller is the solid line position illustrated in FIG. 2 in which the tiller rests upon the tiller support 36.

Secured to the lower end of the cylindrical element 42 by means of threaded element 50 and nut 51 is a downwardly projecting yoke 52, the two arms of which receive a pin 53 which passes through a slot 55 in a link 56. The link 56 is pivoted at one end 57 upon the transom 41 and is provided at its other end with a longitudinally extending slot 60 which receives a pin 61 mounted within the two arms of a yoke 62 secured to the upward end of the shaft 23. It can be appreciated that the gate or slide 21 may be raised or lowered to various positions by raising or lowering the tiller 35. For example, when the tiller 35 is resting upon the tiller support 36 in the solid line position illustrated in FIG. 2, the slide 21 will be in the illustrated solid line position and when the tiller is raised to the dotted line position illustrated in FIG. 2, the slide will also be in the dotted line position illustrated in FIG. 2.

The housing 20 has formed thereon a downwardly and forwardly curved deflector 65. When the gate is moved downwardly to the dotted line position, it completely blocks the flow of the stream of water from the annular member 18 through the bore 26. Because of the fact that the upward portion of the housing 20 is completely sealed or closed off, this water pumped from the turbine must pass downwardly through an opening 66 in the lower end of the housing, this opening facing in a direction generally forwardly of the boat. The boat has a flat element 67 secured to the lower end of its transom 41 and flush with the bottom 70 of the boat and the edge of the opening 66, the flat element preferably being at an angle of seven degrees to the horizontal. However, even an angle as great as that shown and possibly a greater angle is operable. Because of the downwardly and forwardly curving surface 71 of the deflector 65, the water from the turbine moves downwardly and is exhausted in a generally parallel direction to the flat element 67 and passes beneath the boat causing the boat to move rearwardly according to the above mentioned basic law of physics.

It should be noted that the gate 21 is movable to various intermediate positions, one of which will cause the thrust from the turbine to be divided in such a manner as to maintain the boat in a stationary position. When the gate is in such a position, a certain percentage of the water from the turbine passes through the lower portion of the cylindrical aperture 26. The remaining portion of the water from the turbine passes downwardly and is deflected by the member 65 to produce a thrust acting to move the boat rearwardly and equalizing the forward thrust produced by the water passing through the aperture 26. It can be appreciated that the gate 21 may be lowered from this intermediate position to permit a slow rearward movement of the boat and it may be raised from this intermediate position to provide a slow forward movement of the boat.

Fixed to the lower end of the tiller support 36 by means of screws 75 is a radially extending lever 76 which functions as a retainer for tiller support 36 and has fixed to its extending end a depending arm 77. An adjustable link 80 is pivotally connected at its opposite ends to the depending arm 77 and to a lever 81 fixed to the shaft 29A. It can be appreciated that the tiller 35 may be pivoted about a vertical axis extending through the cylindrical element 42 in order to move either one or the other of the deflectors 27 into the jet stream for steering the boat. It should be noted that the yoke 52 is pivotally mounted upon the threaded element 50 so that as the cylindrical element 42 pivots with the tiller 35 and the tiller support

36 when the tiller is used to steer the boat, the yoke 52 will not pivot but instead will retain the position illustrated in FIG. 2 permitting operation of the tiller to raise and lower the gate 21.

5 Mounted upon the distal end of the tiller is a throttle control 85 which may comprise a knob arranged to permit pulling of the knob away from the tiller body or pushing of the knob toward the tiller body to vary the fuel supply to the conventional marine engine 14. Fine 10 adjustment of the throttle is provided by rotation of the knob 35. The throttle control 85 has not been shown in detail inasmuch as it is a commercially available vernier hand throttle type 346-006-18 manufactured by Arens Controls Co. of Chicago, Illinois. The throttle cable 86 15 of the control 85 extends from the control through the tiller to a point adjacent the proximal end of the tiller from which point it extends to and is operatively connected to the engine 14.

From the above description, it can be appreciated that 20 the present invention provides an improved jet boat control means which permits the control of the speed, direction and steering of the jet boat by one hand. All that is necessary to turn the boat is to pivot the tiller horizontally and about the axis of the cylindrical element 42. All 25 that is necessary to speed up or slow down the boat is to push, pull or rotate the throttle control 85 on the end of the tiller. (One convenient method of operating the device involves the arm of the operator resting upon the tiller with the hand surrounding the throttle control 85.) 30 Finally, all that is necessary to raise or lower the gate 21 for reversing or stopping the boat is the raising or lowering of the tiller 35. All of the above controlling operations may be accomplished simultaneously or at different times by the use of one hand and arm according to the 35 desire of the operator.

While the invention has been illustrated and described in detail in the drawings and foregoing description, the same is to be considered as illustrative and not restrictive in character, it being understood that only the preferred 40 embodiment has been shown and described and that all changes and modifications that come within the spirit of the invention and the scope of the claims are also to be protected.

The invention claimed is:

45 1. A control for a watercraft comprising means for moving water in a jet rearwardly of said craft, a blocking element mounted on said craft and selectively movable through a vertical path into said jet to deflect it forwardly of said craft, a deflector pivotally mounted on the 50 craft about a vertical axis, said deflector being positioned to deflect the unblocked jet at various angles in a horizontal plane, a tiller support mounted centrally on said craft at the rearward portion thereof for pivoting about a vertical axis, said tiller support having an axially extending cylindrical aperture, a cylindrical element pivotally received and vertically reciprocal in said aperture, a tiller mounted on said tiller support rearwardly of said cylindrical element for pivoting about a horizontal axis and extending inwardly of said watercraft whereby said 55 tiller may be easily operated by an occupant of said craft, a link pivoted centrally to said tiller support and pivoted at one end of the link to said cylindrical element and at the other end of said link to said tiller whereby vertical movement of said tiller causes vertical movement of said cylindrical element, linking means connecting said cylindrical element and said blocking element whereby vertical movement of said cylindrical element causes vertical movement of said blocking element, and linking means connecting said deflector and said tiller support and so proportioned and arranged that pivoting of said tiller support causes pivoting of said deflector.

60 2. A control as defined in claim 1 in which said water moving means includes a variable speed engine the speed of which may be varied to vary the amount of water in 65 said jet, and a knob mounted at the distal end of said 70 75 link.

tiller, operably connected to said engine and movable to vary the speed of said engine and the amount of water in said jet.
